UNITED STATES PATENT OFFICE.

ALBERT LÜCHINGER, OF NEW YORK, N. Y.

DESIGN FOR AN EMBROIDERY-ALPHABET.

44,727.

Specification for Design.

Patented Oct. 14, 1913.

Application filed July 16, 1913. Serial No. 779,396. Term of patent 3½ years.

To all whom it may concern:

Be it known that I, ALBERT LÜCHINGER, a citizen of Switzerland, residing at the city of New York, county of Bronx, and State of New York, have invented a new, original, and ornamental Design for an Embroidery-Alphabet, of which the following is a specification, reference being had to the accompanying drawing, forming part thereof, and

which represents an embroidery alphabet showing my design.

I claim:

The ornamental design for an embroidery alphabet, as shown.

ALBERT LÜCHINGER.

Witnesses:

ARTHUR E. ZUMPE,
FRIEDA ELMAN.
